(57) **CLAIM**

The ornamental design for a device for accessing a recess of a carrier tape, as shown and described.

DESCRIPTION

FIG. 1 is a perspective view of a new design for a device for accessing a recess of a carrier tape;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken line showing of a device for accessing a recess of a carrier tape is included for the purpose of illustrating portions of a device for accessing a recess of a carrier tape and forms no part of the claimed design.
